BOWLING ALLEY AUXILIARY PLATFORM

Joseph D. Coroniti, Scranton, Pa.

Application June 26, 1953, Serial No. 364,272

2 Claims. (Cl. 273—51)

1

This invention relates to game devices, and more particularly to improvements in bowling alleys.

The main object of the invention is to provide a novel and improved bowling alley accessory for temporarily modifying a regulation bowling alley for use by children, whereby the effective length of the bowling alley is shortened, the improved device being simple in construction, being easy to place in position, and being arranged to protect the underlying surface of the bowling alley on which it is employed.

A further object of the invention is to provide an improved auxiliary player's platform attachment for use with a bowling alley of conventional size, the platform being inexpensive to fabricate, being durable in construction, being comparatively light in weight, and being readily installed when its use is required.

Further objects and advantages of the invention will become apparent from the following description and claims, and from the accompanying drawings, wherein:

Figure 1 is a perspective view of a conventional bowling alley provided with an improved auxiliary player's platform according to the present invention, whereby the bowling alley may be employed by children.

Figure 2 is a perspective view of the player's platform attachment employed in Figure 1.

Figure 3 is an enlarged vertical cross sectional detail view taken on the line 3—3 of Figure 1.

Figure 4 is an enlarged transverse vertical cross sectional view taken on the line 4—4 of Figure 1.

Figure 5 is a perspective bottom view of the auxiliary player's platform attachment employed in Figures 1, 3 and 4.

Figure 6 is a perspective view of a modified form of auxiliary player's platform constructed in accordance with the present invention.

Figure 7 is an enlarged transverse vertical cross sectional view taken on the line 7—7 of Figure 6.

Referring to the drawings, 11 designates a conventional bowling alley of the type having upstanding side walls 12 and 13 and respective gutters 14 and 15 located inwardly adjacent the upstanding walls 12 and 13, the gutters 14 and 15 leading to the usual players' platform 16 located at the end of the alley. The side wall 12 is formed in its top surface with the ball return gutter 17 by means of which the pin boy may return the balls which have been rolled by the player to the forward end of the alley. Balls which have not reached the forward end of the alley will be returned in the gutters 14 and 15 to the players' platform 16.

Designated generally at 18 is an auxiliary players' platform which may be employed to shorten the effective length of the alley, whereby the alley may be used by children. The auxiliary players' platform attachment 18 comprises a generally rectangular board 19 of suitable rigid sheet material such as plywood or the like, the board 19 being dimensioned to fit smoothly between the respective upstanding side walls 12 and 13 of the alley, as shown in Figure 4, with relatively little clearance, the clearance being only that required to readily insert the board between the walls 13 and 14 and to remove same when its use is no longer required. Secured to the bottom surface of the board 19 is a protective layer 20 of cushioning material, such as felt or the like, which is provided to protect the playing surface 21 of the alley. Designated at 22, 22 are respective depending rib members secured to the bottom surfaces of the respective side marginal portions of the platform board 19, the rib elements 22 being spaced so as to be received in the gutters 14 and 15. As shown in Figure 1, the auxiliary platform 19 may be disposed forwardly adjacent the usual players' platform 16, with the ribs 22 received in the gutters 14 and 15. The ribs 22, 22 are each provided on their outer surfaces with a layer of cushioning protective material 23, such as felt or the like, similar to the layers of cushioning material 20 provided on the bottom surface of the board 19.

The auxiliary players' attachment 19 may be of any desired length, depending upon the amount by which it is intended to shorten the effective length of the alley.

Referring now to the form of the invention shown in Figures 6 and 7, the modified form of auxiliary players' platform is designated generally at 18' and comprises a main rectangular body 19' of suitable rigid material, such as plywood or the like, the board 19' having secured to its side marginal portions the respective depending hollow rib elements 22', 22' spaced to be received in the gutters 14 and 15 of the bowling alley. Secured to the bottom surface of the board 19' is the protective layer of cushioning material 20', which may be a sheet of felt or the like. As shown in Figure 7, the protective layer 20' extends between the hollow ribs 22' and the marginal portions of the bottom surface of the board 19'. As is further shown in Figure 7, the hollow ribs 22' project laterally beyond the side edges of the main platform board 19' and secured on the hollow ribs 22' adjacent the side edges of sheet 19' are the filler strips 24 which extend longitudinally on the ribs 22' and which

fill in the space between the side edges of sheet 19' and the outer side edges of the ribs 22'. As in the previously described form of the invention, the depending ribs are provided with protective layers 23 of cushioning material, such as felt or the like secured on the outer surfaces of the ribs to protect the surfaces of the gutters 14 and 15 when the attachment is disposed in operating position on the bowling alley.

As in the previously described form of the invention, the length of the auxiliary platform 18' may be of any desired value, and preferably is of different values for different age groups of children, the auxiliary platform being longer for younger children.

It will be readily apparent that by the use of either of the auxiliary platform attachments above described, a conventional bowling alley may be readily converted for use by children without requiring any permanent physical alteration of the alley, and the auxiliary platform will then enable the alley to be used by children under the usual rules employed in bowling contests. Thus, the foul line will be located at the forward end of the auxiliary platform instead of at the forward end of the fixed players' platform 16.

While certain specific embodiments of improved auxiliary players' platform attachments for use with a bowling alley have been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. An auxiliary players' platform attachment for use with a bowling alley of the type having upstanding side marginal walls and gutters inwardly adjacent said walls leading to a fixed players' platform at the end of the alley com-

5 prising a generally rectangular platform board of rigid sheet material formed to be received between said side marginal walls, a protective layer of cushioning material on the bottom surface of said board, and respective depending rib elements secured in parallel relationship to each other to the bottom surfaces of the respective side marginal portions of said platform board, said rib elements being arranged to be received in said gutters, whereby the platform board may be disposed forwardly adjacent the fixed platform.

2. An auxiliary players' platform attachment for use with a bowling alley of the type having upstanding side marginal walls and gutters inwardly adjacent said walls leading to a fixed players' platform at the end of the alley comprising a generally rectangular platform board of rigid sheet material formed to be received between said side marginal walls, a protective layer of cushioning material on the bottom surface of said board, respective depending hollow rib elements secured in parallel relationship to each other to the bottom surfaces of the respective side marginal portions of said platform board, said rib elements being arranged to be received in said gutters, whereby the platform board may be disposed forwardly adjacent the fixed platform, a plurality of longitudinally extending filler strips secured on the top surfaces of the ribs adjacent the longitudinal edges of the board to define a body substantially fitting between said side marginal walls, and a protective layer of cushioning material on the outer surface of each rib.
